US00D966769S

(12) **United States Design Patent** (10) **Patent No.:** **US D966,769 S**
(45) **Date of Patent:** **** Oct. 18, 2022**

(54) **COFFEE MACHINE**

(71) Applicant: **BEIJING XIAOMI MOBILE SOFTWARE CO., LTD.**, Beijing (CN)

(72) Inventors: **Jing Jiang**, Beijing (CN); **Lei Zhang**, Beijing (CN); **Ningning Li**, Beijing (CN); **Yao Xi**, Beijing (CN)

(73) Assignee: **BEIJING XIAOMI MOBILE SOFTWARE CO., LTD.**, Beijing (CN)

(**) Term: **15 Years**

(21) Appl. No.: **35/511,433**

(22) Filed: **Nov. 20, 2020**

(80) **Hague Agreement Data**

Int. Filing Date: **Nov. 20, 2020**

Int. Reg. No.: **DM/212665**

Int. Reg. Date: **Nov. 20, 2020**

Int. Reg. Pub. Date: **Feb. 19, 2021**

(30) **Foreign Application Priority Data**

May 25, 2020 (CN) 202030247320.3

(51) **LOC (13) Cl.** **07-01**

(52) **U.S. Cl.**

USPC **D7/309**

(57) **CLAIM**

The ornamental design for a coffee machine, as shown and described.

DESCRIPTION

1. Coffee machine

1.1 is a front view of a coffee machine showing the new design;

1.2 is a back view thereof;

1.3 is a left side view thereof;

1.4 is a right side view thereof;

1.5 is a top view thereof;

1.6 is a bottom view thereof;

1.7 is a front perspective view thereof; and

1.8 is a back perspective view.

The broken lines and areas within them depict portions of the coffee machine that form no part of the claimed design.

1 Claim, 8 Drawing Sheets
